UNITED STATES PATENT OFFICE.

WILLIAM D. FRICKS, OF JACKSONVILLE, FLORIDA.

RELEASING MECHANISM FOR TYPE-WRITER TYPE-BARS.

1,076,276.

Specification of Letters Patent.

Patented Oct. 21, 1913.

Application filed October 9, 1912. Serial No. 724,798.

To all whom it may concern:

Be it known that I, WILLIAM D. FRICKS, a citizen of the United States of America, residing at Jacksonville, in the county of 5 Duval and State of Florida, have invented new and useful Improvements in Releasing Mechanism for Type-Writer Type-Bars, of which the following is a specification.

This invention relates to improvements 10 in typewriters and has particular application to a releasing mechanism for typewriter keys.

In carrying out the present invention, it is my purpose to provide a mechanism 15 whereby, in the event of the type bars remaining in writing position against the action of the restoring means, as when two keys are struck simultaneously, the type bars may be restored to normal position.

20 It is also my purpose to provide a releasing mechanism whereby the type bars of typewriting machines may be restored to normal position, in the event of the same remaining in writing position against the action of 25 the restoring means, without necessitating the removal of the typist's hands from the key board. Or should a single type bar remain in writing position against the platen on account of the type bars being 30 too tight in their bearings, same may be restored to normal position.

Furthermore, I aim to provide a releasing mechanism for the type bars of typewriting machines which may be readily applied to any type of machine and which will be simple in construction and reliable and efficient in use.

With the above and other objects in view, the invention consists in the construction, 40 combination and arrangement of parts hereinafter set forth in and falling within the scope of the claims.

In the accompanying drawing, Figure 1 is a top plan view of a typewriter showing 45 my invention applied thereto, and Fig. 2 is a side elevation of the same, parts being broken away.

It is a well known fact that when two or more keys are struck simultaneously, the 50 type bars bind and remain in writing position thereby necessitating the removal of the fingers from the key board to reach the type bars and pull the latter back onto the type bed. By means of my invention, this 55 inconvenience is eliminated and the type bars are restored to normal position without

removing the hands from the key board of the machine.

Referring now to the accompanying drawing in detail, the letter A indicates a 60 suitable form of typewriter including the frame 1, key board 2, type bed 3, type bars 4 pivoted at one end for swinging movement as usual and connected to the type bar sub-lever 5, the universal bar 6 by means of 65 which the escapement mechanism is controlled, as is well known, the universal bar arm 7, and the links 8 adapted to impart movement to the bars through the medium of the type bar sub-levers. 70

My improved type bar releasing mechanism, in the present instance, is manually controlled and comprises what may be termed a type bar throw arm 9, a type bar throw arm shaft 10 to which is rigidly fastened 75 one end of the type bar throw arm 9 and which is journaled for rocking movement in suitable bearings carried by an appropriate part of the typewriter, a pull lever 11 being fastened at one end to the shaft 10, 80 while the opposite end thereof is connected through the medium of a link 12 with the key lever 13 of the margin release key 14. 75

From the foregoing description taken in connection with the accompanying drawing, 85 the construction, mode of operation and manner of employing my invention will be readily apparent. Should two or more type bars stick together, incident to the keys thereof being struck simultaneously, the 90 same may be released and returned to the type bed under the action of the usual restoring means, this release of the type bars being accomplished by depressing the key 14, whereby a rocking motion is transmitted 95 to the shaft 10, through the medium of the link 12 and pull lever 11, with the effect to swing the type bar throw arm 9 into engagement with the universal bar 6, thereby striking the type bar sub-levers 5 whereby 100 the type bars are moved out of contact with one another and to normal position under the action of the restoring means.

In the present form of my invention, I have shown the margin release key 14 of the 105 typewriter as employed for actuating my improved releasing mechanism. It will be understood, however, that this releasing mechanism may be actuated by any other suitable means.

While I have herein shown and described one particular embodiment of my invention 110

by way of illustration, I wish it to be understood that I do not confine myself to the details of construction herein described and delineated, as modification and variation 5 may be made within the scope of the claims and without departing from the spirit of the invention.

I claim:

1. In a typewriter, the combination with 10 the type bars and the universal bar, of means for actuating said universal bar whereby said type bars may be returned to normal position in the event of the same remaining in writing position against the action of the restoring means, said actuating means comprising a type bar throw arm adapted to be 15 swung into engagement with said universal

bar, a rock shaft connected to said arm, a pull lever for actuating said rock shaft, and means for actuating said pull lever. 20

2. In a typewriter, the combination with the type bars, of a release mechanism whereby said bars may be returned to normal position in the event of the same remaining in writing position against the action of the 25 restoring means, and means disposed upon the key board of the typewriter for actuating said releasing mechanism.

In testimony whereof I affix my signature in presence of two witnesses.

WILLIAM D. FRICKS.
